(57) **CLAIM**

The ornamental design for a shoe, as shown and described.

DESCRIPTION

FIG. 1 is a perspective view of a shoe showing my new design;
FIG. 2 is another perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

The dash-dash broken lines surrounding the lightened photographic areas in the drawings depict portions of the shoe that form no part of the claimed design. The figures include textured portions, which are designed to show a stitched fabric of the embodiment's design.
